UNITED STATES PATENT OFFICE.

LLOYD F. SCHRADER, OF NEW YORK, N. Y., ASSIGNOR TO FOUNDATION OVEN CORPORATION, OF NEW YORK, N. Y., A CORPORATION OF NEW YORK.

REVERSING MECHANISM FOR BY-PRODUCT COKE OVENS.

Application filed September 22, 1919. Serial No. 325,570.

To all whom it may concern:

Be it known that I, LLOYD F. SCHRADER, a citizen of the United States, and residing in New York, N. Y., have invented certain new and useful Improvements in Reversing Mechanism for By-Product Coke Ovens, of which the following is a specification.

My invention provides certain improvements in reversing mechanisms for coke ovens in the direction of economy of construction and ease of operation and maintenance.

The accompanying drawings illustrate an embodiment of the invention.

Fig. 1 is a side elevation of the lower part of a coke oven to which the invention is applied, the central portion being cut out;

Fig. 2 and Fig. 3 are enlarged details thereof;

Fig. 4 is a plan of the same;

Fig. 5 is an end elevation of the same.

Fig. 6 is an enlarged detail thereof.

Referring to the embodiment of the invention illustrated, the oven as a whole is designated by the numeral 2. Along the sides thereof there is arranged a number of gas valves 3, one for each coking chamber and a corresponding number of air valves 4. The gas valves for example may be of the type shown in Fig. 2. Gas is admitted from a main 5 and passes through pipes 6 and 7 alternately to flues in the partition walls of the oven. The operating arm 8 of the valve has a forked end through which passes an operating rod 9 with collars 10 and 11 thereon to strike the arm 8 as the rod is reciprocated and throw it first to one side and then to the other.

The air valve 4 shown in Fig. 3 communicates at its lower end with the waste gas flue 12 and at the rear side with an air flue of the oven. It is operated by a reciprocating stem 13 connected by a link 14 to a bent lever 15 which is forked at its end and engaged between collars 16 and 17 on a reciprocating operating rod 18.

The valves shown are only typical. A variety of valves and valve mechanism are in common use and may be substituted for those shown. In the operation of the coke oven it is reversed at certain intervals to pass the waste gas through regenerators in order to heat the latter and to pass fresh air through other regenerators which have

been thus heated in the previous stage. When the air is reversed the gas is also reversed so as to supply it to the flues which are now receiving fresh air and to cut it off from those through which the burnt gases are now passing to the regenerators.

My invention provides for a single operating motor connected both to the gas and air reversing valves so as to reverse them all at the same operation. The ports of the gas and air valves and the throw of the controlling parts thereof may be arranged as desired to cut off the gas slightly before cutting off the air for each flue, and to restore the air admission before the gas admission; or to provide for air and gas cut off and admission in any desired relation. A single motor however is used for operating all the valves and at each stroke reversing them all. For this purpose I use an electric motor 19, Fig. 5, mounted at one end of the furnace and driving gearing within a casing 20. The driven shaft 21 has on its opposite projecting ends arms 22 and 23 at the ends of which are pivoted links 24 and 25 connected to cables 26 and 27 which control the operating rods 18 and 19 respectively of the valves.

The cables 26 extend over guide pulleys 28 and 29 to the forward ends of the operating rods 18 for the air valves on opposite sides of the oven. At the rear ends of these rods they are connected to each other by a cable 30 which runs over guide pulleys 31 at the rear and is provided with a turn buckle to take up the slack.

The cables 27 extend over similar guide pulleys 32 and 33 to the forward ends of the gas valve operating rods 9, and the latter are connected together at their rear ends by a cable 34 which extends around pulleys 35 and is provided with a turn buckle 36, Fig. 4. Turn buckles 37 and 38 are provided also in the cables 26 and 27 for taking up the slack.

As the motor rotates the crank arms 22 and 23 throw the cables and valve operating rods for the gas valves in one direction and for the air valves in the opposite direction so that they first stand in the positions, Figs. 2 and 3, and are reversed at each operation of the motor. The motor is operated about once every half hour to effect the desired reversal.

Though I have described with great par-

ticularity of detail a specific embodiment of my invention, yet it is not to be understood therefrom that the invention is restricted to the particular embodiment disclosed. 5 Various modifications thereof in detail and in the arrangement of the parts may be made by those skilled in the art without departure from the invention as defined in the following claims.

10 What I claim is:

1. Mechanism for operating the air and gas valves of a coke oven, said mechanism including in combination actuating devices for said valves and a common motor for reversing at the same time the actuating devices for both sets of valves.
2. Mechanism for operating the air and gas valves of a coke oven, said mechanism including in combination reciprocable rods 15 for reversing said valves and a common motor for reciprocating said rods at the same time.

3. Mechanism for operating the air and gas valves of a coke oven, said mechanism including in combination reciprocable rods 25 for reversing said valves, a motor and a driven shaft rotated thereby and crank arms on the opposite ends of said shaft connected to the respective rods to reciprocate them at the same time. 30

4. Mechanism for operating the air and gas valves of a coke oven, said mechanism including in combination reciprocable rods for reversing said valves and a reversing device adapted to be actuated at suitable 35 intervals, said rods being connected directly to said reversing device so as to be moved simultaneously when the reversing device is actuated.

In witness whereof I have hereunto signed my name.

LLOYD F. SCHRADER.
